UNITED STATES PATENT OFFICE.

WILLIAM ELLIOTT KARNS, OF PARKERS LANDING, PENNSYLVANIA.

INSULATING END POST FOR RAIL-JOINT CIRCUITS.

No. 874,206.

Specification of Letters Patent.

Patented Dec. 17, 1907.

Application filed January 29, 1907, Serial No. 354,635. Renewed September 23, 1907, Serial No. 394,203.

To all whom it may concern:

Be it known that I, WILLIAM ELLIOTT KARNS, a citizen of the United States, residing at Parkers Landing, in the county of 5 Armstrong and State of Pennsylvania, have invented certain new and useful Improvements in Insulating End Posts for Rail-Joint Circuits, of which the following is a specification.

10 This invention relates to the subject of electrical conductor insulators, and has special reference to the subject of insulating the ends of track rails in insulated rail joints.

To this end the invention contemplates a 15 simple and practical construction of insulating end post adapted to be interposed between the contiguous ends of the adjacent rails in a rail joint and providing means for effectually maintaining insulation at this point at all 20 times and under all conditions of service.

Furthermore, the invention contemplates a construction of insulating end post which will readily accommodate itself to the contraction and expansion of the rails, and is so 25 arranged with reference to the running surfaces of the rails as not to be injured or crushed by the breaking down of the ends of the rails as commonly occurs from the pounding of the wheels traveling thereover.

30 Another and important object of the invention is to provide an insulating end post having a main indurated or hardened body portion and a yielding or soft tip, the latter being at the extreme top edge or edges of the 35 post and serving to receive and cushion any shock or pounding to which the post might be subjected, thereby greatly increasing the life or durability thereof as an effective insulating medium between the rail ends.

40 With these and many other objects in view, which will more readily appear as the nature of the invention is better understood, the same consists in the novel construction, combination, and arrangement of parts hereinafter more fully described, illustrated, and 45 claimed.

The essential features of the invention involved in carrying out the objects above indicated are necessarily susceptible to structural 50 modification without departing from the scope of the invention, but a preferred embodiment thereof is shown in the accompanying drawings, in which—

Figure 1 is a side elevation of an insulated 55 rail joint embodying the present invention. Fig. 2 is a longitudinal sectional view of the

same. Fig. 3 is a cross sectional view through the center of the joint on the line 3—3 of Fig. 2. Fig. 4 is a detail in perspective of the double form of end post preferably employed. 60 Fig. 5 is a sectional perspective view of the single form of post embodying the yielding or soft tip.

Like references designate corresponding parts in the several figures of the drawings. 65

In carrying out the present invention, no change is required in the construction of insulated joint to which the improved end posts may be applied, so for illustrative purposes there is shown in the drawings a simple 70 type of insulated rail joint embodying in its organization the service rails 1 and 2, the side joint or angle bars 3, the joint bolts 4, the bolt insulation 5, and the side insulating sheets 6, which latter are interposed between 75 the rail sides and the side joint plates 3.

The insulating end post contemplated by the present invention is made of insulating material of any suitable or approved character, but preferably of the plain rubber or 80 rubber and canvas compositions which are usually employed for insulating purposes between the ends of rails and rail joints. Irrespective of the nature of the insulating material employed, the construction and functions of the improved end post always remain the same.

One of the preferable and practical forms of the end post is shown in Figs. 1, 2, 3, and 4 of the drawings and consists of a double or 90 duplex end post body designated in its entirety by the reference letter P and comprising a pair of yieldingly separated duplicate insulating strips 7 united at their bases, as at 8, and upwardly divergent from the 95 latter point, whereby the post body will have a spring action and thereby serve to hold the opposite members or strips 7 yieldingly in contact with the rails ends so as to maintain an effective insulation under all conditions, 100 and causing the post to adapt itself to the contraction and expansion of the rails without losing contact therewith.

Each of the separate insulating strips or members 7 is of a size and design corresponding substantially to the size and form of the cross section of the rails, so that the end post, when in position, follows the contour or outline of the rail sections, thus providing a complete and effective end insulation. By 105 reason of this correspondence in shape between the end post and the rail ends, each

end post strip or member 7 comprises a rail head element 9, a rail base flange element 10, and a narrow connecting web 11 preferably forming an integral part of, and connecting the head and base flange elements 9 and 10. In the duplex or double form the bases or base flanges 10 of the separate strips or members 7 are united by vulcanization or other means so long as the strips or members 7 above their bases are permitted to have a spring action and are normally separated for the purposes explained.

An important feature of the invention resides in having the end post body of less height than the rails so that the tops or upper edges of the end post will be disposed below the running surfaces of the rails so as to minimize the danger of crushing the post by the pounding of the car wheels, but to positively protect the post against that result, the invention involves the improved feature of forming the head element 9 of each member 7 with a yielding or soft rubber tip 12. This soft tip 12 is vulcanized or otherwise formed on or with the harder or indurated portion of the head element 9, but is preferably formed by the process of vulcanization so as to be practically an integral part of the post body while at the same time being materially softer and sufficiently yielding so as to receive shocks or knocks without injury to the post.

In Fig. 3 the dotted line 13 indicates the line of separation between the indurated and soft portions of the end post head, while the different hatching in the sectional views accentuate the nature of the soft tip 12. The end post can be used in the single form shown in Fig. 5 of the drawings, and in as much as the construction of the single end post is the same as the individual members 7

shown in Fig. 4, similar reference characters will apply to similar parts.

I claim:

1. An insulating end post for rail joints, 45 consisting of an indurated body having a soft tip on the head thereof.
2. An insulating end post for rail joints having a soft tip.
3. An insulating end post for rail joints 50 having an integral soft tip.
4. An insulating end post for rail joints having a soft tip on the head thereof.
5. An insulating end post having a head element provided with an indurated portion 55 and a soft portion.
6. An insulating end post for rail joints comprising an indurate body in the form of the cross section of the rail having the tip portion of its head formed of relatively soft 60 yielding material.
7. An insulating end post for rail joints comprising a pair of yieldingly separated duplicate insulating strips in the form of the cross section of a rail. 65
8. An insulating end post comprising a body having a pair of yieldingly separated insulating members united at their bases and divergent from their point of connection, each of said members being in the form of 70 the cross section of a rail.
9. In an insulated rail joint, the combination with the joint members, of an insulating end post interposed between the rail ends and comprising a spring body having a soft 75 tip and of less height than the rail sections.

In testimony whereof I hereunto affix my signature in the presence of two witnesses.

WILLIAM ELLIOTT KARNS.
